L. DE GOLL.
CIGARETTE CASE.
APPLICATION FILED SEPT. 16, 1916.

1,245,445.

Patented Nov. 6, 1917.

Inventor

Louis de Goll,

By John H. Volk,
his Attorney

UNITED STATES PATENT OFFICE.

LOUIS DE GOLL, OF VAN BIBBER, MARYLAND.

CIGARETTE-CASE.

1,245,445.

Specification of Letters Patent.

Patented Nov. 6, 1917.

Application filed September 16, 1916. Serial No. 120,471.

To all whom it may concern:

Be it known that I, LOUIS DE GOLL, a citizen of the United States, residing at Van Bibber, in the county of Harford and State 5 of Maryland, have invented certain new and useful Improvements in Cigarette-Cases, of which the following is a specification.

The primary object of this invention is the production of a cigarette case in which 10 both cigarettes and matches may be securely and safely carried, and wherein these may be rendered readily accessible when the case is opened.

In order to more fully describe my invention, reference will be had to the accompanying drawings in which,

Figure 1, is a vertical sectional elevation of one specific embodiment of my invention showing the case open;

20 Fig. 2, a front elevation thereof;

Fig. 3, an end elevation of the case closed, and

Fig. 4, a horizontal section on line 4^x-4^x, Fig. 2.

25 My invention in the form shown, comprises, among other parts, an outer container composed of solid end pieces 1 and 2 to which is secured a preferably continuous piece of leather, leatheroid, flexible card- 30 board or other desired material 3, forming the front and back and a flap 4. The back of the container extends higher than the front for purposes which will more fully appear later. Slidable in this outer container is an inner member comprising, among other parts, a corrugated cigarette tray or holder 5, having along its upper portion a flexibly connected section or flap 6 adapted to form a hinged backing for the 35 upper portion of the cigarettes and provided with a finger tab 7. The cigarette tray or holding member 5 has a flap 8 extending from its lower edge and adapted to lie against the face of the cigarettes when 40 the tray is pushed down into the outer container.

On the outer face of flap 8 is an elongated match pocket 9 divided into sections by vertical partitions 10. These partitions limit 50 the extent to which the matches may tilt sidewise and thereby prevent their heads from coming in contact with the scratching surface hereinafter described.

The matches are protected by a flap 11 55 flexibly attached along the upper edge of the match pocket and carrying exposed on

its inner face match scratching material 12, the ends of which extend into slots or pockets 13.

The movement of the cigarette tray with 60 its match flap is limited, in the outer container, in an outward direction by two tapes or ribbons 14 secured at one end to the outer container near its bottom and at the other to said tray.

Also attached to the outer container near 65 its bottom is a tape or ribbon 15 which is attached at its other end fast to the match protecting flap 11.

As previously pointed out, the back of 70 the outer container extends higher than the front. Therefore, when the cigarette tray is pulled out to a certain point, tape 15 will first cause the match protecting flap 11 to swing downward and expose both the 75 matches and scratching material 12, and if the tray be pulled out farther, the match carrying flap 8 will automatically open away from the cigarettes, but the latter is not necessary in order to readily take a 80 cigarette from the tray.

The parts all readily close when the tray is pushed down into the outer container.

While I have here shown and described 85 but one specific embodiment of my invention, it should be understood that the same may be modified without departing from the spirit thereof.

What I claim is:

1. A device of the class described, comprising an outer container, an inner member 90 slidable in said container and comprising two sections flexibly connected to each other at their bottoms, one of said sections having corrugations adapted to receive cigarettes and the other of said sections having 95 match holding means and a flap adapted to extend over the matches and provided with a match scratching surface on its inner face, a tape forming a connection between said 100 inner member and said outer member for limiting the movement of said inner member as a whole outward in said outer member, and a tape forming a connection between said match flap and said outer member for 105 opening said flap from the matches when said inner member is moved outwardly, substantially as described.

2. A device of the class described, comprising an outer container, an inner member 110 slidable in said container and comprising two sections flexibly connected to each other

- at their bottoms, one of said sections having corrugations adapted to receive cigarettes and the other of said sections having match holding means and a flap adapted to 5 extend over the matches, a tape forming a connection between said inner member and said outer member for limiting the movement of said inner member as a whole outward in said outer member, and a tape forming 10 a connection between said match flap and said outer member for opening said flap from the matches when said inner member is moved outwardly, substantially as described.
- 15 3. A device of the class described, comprising an outer container, a cigarette tray slidable in said container and having a flap adapted to extend over the cigarettes and to be forced toward the cigarettes by frictional 20 engagement with a side of the outer container, and a flexible connection between said flap and said outer container adapted to withdraw said flap outwardly from the cigarette tray when the latter is pulled outwardly in said outer container.
- 25 4. A device of the class described, comprising an outer container, an inner member slidable in said container and com-
- prising two sections flexibly connected to each other at their bottoms, one of said sections having corrugations adapted to receive cigarettes and the other of said sections having match holding means and a flap adapted to extend over the matches, and a flexible connection between said match flap 30 and said outer member adapted to withdraw said flap outwardly from said matches when said inner member is pulled in one direction, substantially as described.
5. A device of the class described, comprising an outer container, a corrugated cigarette tray slidable in said container and having a flap adapted to extend over the cigarettes, a match pocket carried by said flap, a flap flexibly attached to said first flap 40 and adapted to cover said match pocket and means to automatically open said match flap as the said tray is slid outwardly in said outer container.

In testimony whereof I affix my signature 50
in the presence of two witnesses.

LOUIS de GOLL.
